CLAIM

The ornamental design for a baseball strike zone indicator, as shown and described.

DESCRIPTION

FIG. 1 is a top plan view of a baseball strike zone indicator showing my new design;

FIG. 2 is a bottom plan view of the baseball strike zone indicator;

FIG. 3 is a side view of the baseball strike zone indicator;

FIG. 4 is an inverted rear elevational view of the baseball

strike zone indicator; and,

FIG. 5 is a front elevational view of the baseball strike zone indicator.
